SWITCHING MECHANISM FOR MULTIPLE
FREQUENCY BAND RECEIVERS

William A. Schaper, Cicero, and George B. McClellan, Chicago, Ill., assignors to Johnson Laboratories, Inc., Chicago, Ill., a corporation of Illinois

Application April 8, 1940, Serial No. 328,458

4 Claims. (Cl. 200—11)

This invention relates to switching mechanism for radio receivers, such as those used for the reception of broadcasting, and more particularly to receivers intended to cover a very wide range of frequencies, or plural bands extending over the important portions of such a wide range. The invention provides means by which the very considerable advantages of permeability tuning may be secured in such wide band receivers.

The switching arrangements which we employ with our novel coil system are different from, although not necessarily more complicated than, those employed in systems in which separate inductive windings are employed for each wave band. These switching arrangements, together with such modifications thereof as will readily occur to those skilled in the art, taken in connection with the coil system per se constitute the novel structure which when employed with other components already well known, to form variably tunable resonant circuits, makes possible the production of highly efficient permeability-tuned plural-band wide-range radio receivers in accordance with the invention.

In order that the principle underlying our invention may be properly understood, we shall first describe a coil system which provides four different air-core inductance values, and we shall then show how this coil system, or modifications thereof, may be employed in practical receivers, reference being had to the accompanying drawings, in which:

Fig. 1 is a diagrammatic representation of a type of winding in accordance with the invention, suitable for providing four different air-core inductance values;

Fig. 2 is a diagram showing a switching method in accordance with the invention, suitable for employment with the winding of Fig. 1;

Fig. 3 is a side elevation of a coil structure having a winding such as that of Fig. 1 and a portion of the switch gear of Fig. 2;

Fig. 4 is an end view of the coil structure of Fig. 3;

Fig. 5 is a schematic diagram of a receiver embodying the invention; and

Figs. 6 and 7 are an elevation and a section on the line 1—1 of the elevation, respectively, of a switching arrangement to carry out the changes diagrammatically indicated in Fig. 2.

Figure 1 shows a construction which is suitable for use with our invention with a coil system in the case in which four different inductance values are to be provided. The coil comprises 55 eight windings arranged spirally side by side in

a single flat layer upon a suitable tube. In the figure, the lower ends of these eight windings are numbered 1 to 8 respectively, the corresponding upper ends being numbered 1' to 8' respectively, this same notation being used in Figs. 2, 3, 4 and 6. It is preferable that the windings be spaced from each other by a distance approximately equal to the diameter of the conductive portion of the wire employed, which may be either solid wire or conductor having plural insulated strands. In Fig. 1, for clarity, the ends of the eight windings are shown as all leaving the form or tube at the same angular point, but it will be understood that they are preferably brought off at eight equiangularly spaced points.

The eight windings of Fig. 1 may be made to produce numerous inductance values by connecting them in various series, parallel, and 20 series parallel arrangements.

Fig. 2 shows the eight windings of Fig. 1 connected in four different ways, indicated by the letters a, b, c and d. End 1 of the first winding is one terminal of the inductor, and end 8' of the eighth winding is the other terminal of the inductor. For convenience of explanation, end 1 is shown as connected to a bus 9, and end 8' is shown connected to a bus 10, and the remaining terminals are each shown as connected to switch arms by which they may be connected either to a bus, or to the opposite end of the next adjacent winding.

Maximum inductance is secured by placing the eight windings in series aiding relation, as 35 shown in Fig. 2a, by connecting the upper end of each winding to the lower end of the next adjacent winding. To secure the next lower value of inductance, the windings are thrown into two groups each having four windings in series. This is accomplished, as shown in Fig. 2b, by switching end 5 to bus 9 and end 4' to bus 10. To secure the next lower value of inductance, the windings are thrown into four groups each 40 having two windings in series. This is accomplished, as shown in Fig. 2c, by switching ends 3, and 7 to bus 9, and ends 2' and 6' to bus 10. To secure the lowest value of inductance all eight windings are placed in parallel. This is 45 accomplished, as shown in Fig. 2d, by switching ends 2, 4, 6 and 8 to bus 9, and ends 1', 3', 5' and 7' to bus 10.

Still referring to Fig. 2, and having in mind the coil shown in Fig. 1, it will be observed that if the upper ends of each of the eight windings 50 are returned, for example by bus bars, to the

lower end of the structure, then the switching may be accomplished entirely at the lower end. A convenient structure for securing this result and mounting the switching mechanism, is shown in Figs. 3 and 4. The eight windings of Figs. 1 and 2 are wound upon a suitable thin-walled tube 11 of insulating material, core 12 being arranged to slidably enter tube 11 from the far end thereof. At either end of tube 11 there are discs 13 and 14, also of insulating material, and running between these discs, staked or otherwise suitably fastened into equi-angularly spaced holes around the peripheries thereof are small wire bus bars 1" to 8" inclusive. The ends 1' to 8' inclusive, of the eight windings are soldered respectively to bus bars 1" to 8" inclusive and are thus returned to the opposite end of the form, where the bus bars are terminated in suitable switch contact points. The ends 1 to 8 inclusive, of the eight windings are connected directly to eight switch-points, also equi-angularly spaced, but at a smaller radius than the bus bars. It will be apparent that by bringing suitable sets of switch-arms into contact with switch-points 1 to 8 and 1' to 8', the four different connections of the windings explained in connection with Fig. 2 can be secured, and switching of the associated capacitors can be accomplished in the same switch-gear.

It will be noted that for all four inductance values each of the switch-points in Fig. 2 is connected either to an adjacent switch-point or to one terminal of the complete coil. Thus switch-point 4' is connected to switch-point 5 for position *a* of Fig. 2 and to bus bar 10 (not shown in Figs. 3 and 4) for positions *b*, *c* and *d* of Fig. 2. Similarly, switch-points 2' and 6' are connected respectively to switch-points 3 and 7 for positions *a* and *b*, and to bus bar 10 for positions *c* and *d*. And finally, switch-points 1', 3', 5' and 7' are connected respectively to switch-points 2, 4, 6 and 8 for positions *a*, *b* and *c* and to bus bar 10 for position *d*. Switch-points 2 to 8, when not connected to switch-points 1' to 7' respectively as just described, are connected to bus bar 9.

Our improved switching mechanism is illustrated in Figs. 6 and 7 to be employed in combination with a coil structure such as that shown in Figs. 3 and 4 to secure the switching functions indicated diagrammatically in Fig. 2. In Fig. 6, switch contact points 2-8 and 1'-7' are arranged in seven radial pairs, spaced 45 degrees apart in the same manner as in Fig. 4, upon a suitable disc of insulating material which may be the end disc 14 of the form shown in Figs. 3 and 4. The eight windings of a coil such as that shown in Fig. 1 are shown connected, each from an inner switch contact point to the adjacent outer switch contact point, proceeding always in a clockwise direction (or vice versa) except for terminals 1 and 8' to be described later. Inwardly of the radial pairs of contact points, there is a contact ring 36 corresponding to bus 9 of Fig. 2. Outwardly of the radial pairs of switch contact points, there is a ring 37, which corresponds to bus 10 of Fig. 2. Positioned over the switch contact points and the rings 36 and 37 are seven radially movable arms 38-44 of insulating material. In the drawing, arms 38, 39 and 40 are broken away to show the radial pairs of switch contact points. Each of these arms carries two contactors, 45, which have pins 46 which engage holes in the arms. Also positioned in the arms are follower pins 47 which engage

cam slots 48-54 in ring 37. Contactors 45 are of such shape that in the outward position of each arm, the inner contactor connects together the corresponding radial pair of switch contact points, while the outer contactor rests upon the ring 37. Upon moving the arm inwardly, the inner contactor connects the inner switch contact point to contact ring 36, and the outer contactor connects the outer switch contact point to the ring 37.

Ring 37 is rotatably supported in peripheral guides, not shown, and has gear teeth 55 around 15 degrees of its periphery, which engage a pinion 56 mounted upon a shaft 57 to which an operating knob, not shown, may be attached. Arms 38-44 are restrained to radial motion in slots in upwardly projecting inner rim 58 of ring 36 and by similar slots in guide members 59 at their outer ends.

20 Cam slots 48-54 are so shaped that upon rotation of ring 37 through successive angles of 11.25° the four different connections shown in Fig. 2 of the eight windings of a coil such as shown in Fig. 1 are accomplished. In the position shown in 25 Figs. 6 and 7, the connections correspond to those of Fig. 2a, all eight windings being connected in series. Cam slot 51 is of such shape that immediately upon clockwise rotation of ring 37 arm 41 is moved inwardly to connect switch contact point 4' to ring 37 and switch contact point 5 to ring 36, to secure the arrangement of Fig. 2b. Upon further rotation of ring 37, arm 41 remains in its inward position and arms 39 and 43 are moved inwardly to secure the arrangement of Fig. 2c. Upon still further rotation of ring 37, arms 39, 41 and 43 remain in their inward positions and arms 38, 40, 42 and 44 are moved inwardly to secure the arrangement of Fig. 2d. Upon counterclockwise rotation of ring 37 the 40 reverse operations occur. Suitable notches and a pawl, not shown, may be provided to indicate the four positions of ring 37, and to hold the ring in a selected position. A suitable stop, not shown, may be provided either on ring 37 or on 45 shaft 57 to prevent rotation of ring 37 beyond its proper end positions.

50 Terminal 1 of the first winding is permanently connected to ring 36, and terminal 8' of the eighth winding is permanently connected to ring 37. The ungrounded terminals of condensers 16, 17, 18 and 19 of Fig. 5, are brought to contact points 60, 61, 62 and 63 respectively of the switch in Fig. 6. Mounted upon ring 37 and rotating therewith in a small contactor 64. As 55 ring 37 is rotated to select a desired connection of the coil windings, contactor 64 moves over contacts 60-63 to connect the appropriate condenser into circuit, as explained in connection with Fig. 5. For convenience in the drawings, 60 ring 37 is shown radially outside the switch contact points and in the same plane, but it may alternatively be made of an outside diameter corresponding to the outer circle of switch contact points and may be positioned above them, by 65 suitable repositioning of the contactors 45 and the follower pins 47.

In the switch gear shown by way of illustrative example in Figs. 6 and 7, ring 37 acts as a rotary cam to actuate arms 38-44 and also as a bus bar and electrical terminal of the compound coil. If preferred, ring 37 may be made of insulating material, and a separate ring of suitable contact metal may be added to act as a bus corresponding to bus 10 of Fig. 2. Numerous other modifications will occur to those skilled in the art.

As is known, the inductance change produced by a particular core depends upon the dimensions and proportions of the coil with which it is used, but is independent of the inductance value of the coil. Thus, using a single core, the inductance change and therefore the ratio of maximum-to-minimum frequency will be essentially the same for all four air-core inductance values, and for all four frequency bands, or for as many frequency bands as may be employed.

However, the losses introduced in the circuit due to the presence of the core at the lower frequencies in each band will, in general, be greater in the higher frequency bands. This fact makes advisable a compromise in the choice of the material from which the core is made, so that the inductance-to-resistance of the circuit will be decreased by the core only in the highest frequency band, or the two highest frequency bands, will remain substantially constant in the second or third band, and will be increased in the fourth or lowest frequency band. It is to be remembered that the coil construction in accordance with the invention provides exceptionally good quality coefficient, Q , on the higher frequency bands, so that while the change in Q over the frequency band is more pronounced in the higher frequency bands, nevertheless very satisfactory gain and selectivity can be secured in all bands.

Fig. 5 is a schematic diagram of a receiver embodying the invention, of the superheterodyne type, and employing a series-tuned antenna circuit and an oscillator circuit, followed by the usual oscillator-modulator, intermediate-frequency amplifier, detector, audio-frequency amplifier and loud speaker as indicated. Coils, and switch-gear to accomplish the necessary inductance and capacitance changes for the different frequency bands, of the type above described are indicated by the blocks marked "Antenna coil and switch" and "Oscillator coil and switch." The antenna 15 is permanently connected to one terminal of the antenna coil, the other terminal of the coil being connected to a grid of the oscillator-modulator tube. The antenna coil switch automatically selects one of the condensers 16, 17, 18 or 19 for the selected frequency band. The oscillator circuit is of conventional type, and as shown employs shunt coils 20 and 21 and series coils 22 and 23 on the two lower frequency bands respectively, capacitors 24 and 25 being connected permanently across shunt coil 20 and capacitors 26 and 27 being permanently connected across shunt coil 21. The proper complete combination of shunt coil, series coil, and capacitors is selected by the coil switch. Similar shunt and series coils may also be employed on the two higher frequency bands, although they are usually not necessary. As shown, for the two higher frequency ranges, the oscillator circuit employs capacitors 28-29 and capacitors 30-31 respectively. The antenna coil switch and the oscillator coil switch are mechanically connected for simultaneous operation by means of a single knob, as indicated by the dotted line 32. Ferromagnetic cores 33 and 34 are associated with the antenna coil and the oscillator coil respectively and are arranged for movement in unison relative to the coils by means of a single knob as indicated by dotted line 35.

It will be understood that the showing of Fig. 5 is merely intended to be exemplary of the manner in which the invention is to be employed in a practical receiver, and that many modifications within the scope of the invention

will occur to those skilled in the art. For example, the arrangement according to the invention may equally well be employed in parallel-tuned input circuits, and in either the plate circuits or the grid circuits of tuned radio-frequency amplifier stages. Additionally, as already noted, the arrangement according to the invention may be employed in receivers having less than four frequency bands, and in cases in which it is preferred to employ separate coils permanently connected as above described.

In the detailed description of our invention we have chosen an arrangement for providing four frequency bands, since this example is adequate to illustrate the principles involved. It will be understood, however, that the invention is not limited to a maximum of four frequency bands, and that it may be applied to five or more bands as may be required.

Having thus described our invention, what we claim is:

1. As a means for selectively connecting a plurality of permeability tuned inductance coils in different ones of series, parallel and series-parallel arrangements, the combination of a mounting plate, concentric flat metal rings mounted on said plate and spaced from each other radially by a substantial amount, pairs of electrical contacts for connection with the terminals of said coils and each pair mounted on said plate between said rings and spaced therefrom and from each other, said rings constituting bus-connections for the selective connecting means, movable switch arms having conductive contactors for selectively connecting said electrical contacts and said rings, and cam mechanism for actuating said switch arms.

2. As a means for selectively connecting a plurality of permeability tuned inductance coils in different ones of series, parallel and series-parallel arrangements, the combination of a mounting plate, concentric flat metal rings mounted on said plate and spaced from each other radially by a substantial amount, pairs of electrical contacts for connection with the terminals of said coils and each pair mounted on said plate between said rings and spaced therefrom and from each other, said rings constituting bus-connections for the selective connecting means, movable switch arms having conductive contactors for selectively connecting said electrical contacts and said rings, and cam mechanism for actuating said switch arms, said switch arms being mounted on said plate in radial arrangement for longitudinal movement and respectively in line with said pairs of contacts.

3. As a means for selectively connecting a plurality of permeability tuned inductance coils in different ones of series, parallel and series-parallel arrangements, the combination of a mounting plate, concentric flat metal rings mounted on said plate and spaced from each other radially by a substantial amount, pairs of electrical contacts for connection with the terminals of said coils and each pair mounted on said plate between said rings and spaced therefrom and from each other, said rings constituting bus-connections for the selective connecting means, movable switch arms having conductive contactors for selectively connecting said electrical contacts and said rings, and cam mechanism for actuating said switch arms, said switch arms being of insulating material and each of said contactors being adapted to electrically connect

adjacent ones of said rings and contacts, said switch arms being mounted on said plate in radial arrangement for longitudinal movement and respectively in line with said pairs of contacts.

4. As a means for selectively connecting a plurality of permeability tuned inductance coils in different ones of series, parallel and series-parallel arrangements, the combination of a mounting plate, concentric flat metal rings mounted on said plate and spaced from each other radially by a substantial amount, pairs of electrical contacts for connection with the terminals of said coils and each pair mounted on said plate be-

5
10
tween said rings and spaced therefrom and from each other, said rings constituting bus-connections for the selective connecting means, movable switch arms having conductive contactors for selectively connecting said electrical contacts and said rings, and cam mechanism for actuating said switch arms, each pair of said contacts cooperating with one of said switch arms and constituting terminal connections one for each to two of said coils.

WILLIAM A. SCHAPER.
